UNITED STATES PATENT OFFICE.

JOHN J. DAVIS, OF YOUNGSTOWN, OHIO, ASSIGNOR TO THE WILLIAM TOD COMPANY,
OF YOUNGSTOWN, OHIO, A CORPORATION OF OHIO.

RECEIVING-TABLE.

1,117,004.

Specification of Letters Patent. Patented Nov. 10, 1914.

Application filed June 20, 1912. Serial No. 704,810.

To all whom it may concern:

Be it known that I, JOHN J. DAVIS, a citizen of the United States, residing at Youngstown, in the county of Mahoning 5 and State of Ohio, have invented certain new and useful Improvements in Receiving-Tables, of which the following is a specification.

This invention relates to receiving tables 10 for rolling mills and particularly to a manipulating device adapted to move bars or billets to any desired position on the table to stand the same on edge or turn them over according to the requirements of the situation.

Broadly stated the device may be said to consist of a series of guide fingers of peculiar formation and a series of lugs, the lugs and the guide fingers being mounted 20 to move, relatively one to the other, transversely across the receiving table. The lugs and fingers are adapted to engage a bar or billet lying between them, and when moved toward each other the lugs force the bar or billet against the guide fingers in such manner as to turn the bar or billet about its longitudinal axis so that it may be turned over or stood upon edge as may be desired.

The preferred embodiment of my invention is illustrated in the accompanying drawings in which:

Figure 1 is a plan view of the receiving roll table with my invention applied; Fig. 2 is a transverse section of the same on the 35 line 2—2 of Fig. 1; Fig. 3 is a perspective view designed to illustrate the mode of engagement of the lugs with the bar or billet to hold the same on edge; and Fig. 4 is a partial view similar to the corresponding 40 portions of Fig. 2 but showing the short or overturning lug in operative relation with a guide finger.

In the drawings, 1 represents the frame of the roll table which is supported on any suitable foundation and in which are journaled rollers 2 driven from a common shaft 3 by the bevel gears 4, as is well understood in the art. I do not confine myself, however, to the particular form of receiving table 50 shown, as my invention might readily be applied to other forms.

On one side of the table and parallel with the shaft 3 is mounted a shaft 5 which turns in bearings 6 carried on foundations 7, as 55 shown in Fig. 2. Fast on the shaft 5 are

sprockets 8, two being shown in the drawings, and alined with the sprockets 8 are similar sprockets 9 mounted on bearing brackets 10 which are preferably carried on the frame 1, though they might be supported in any other suitable manner. Passing around the sprockets 8 and 9 are chains 11, each chain being provided with an up-standing curved guide finger 12 of substantially the form shown in the drawings, the curvature of the finger being determined by the size and form of the material handled.

At the opposite side of the machine from the shaft 5 is a parallel shaft 13 turning in bearings 14 as shown. Between these bearings are sprockets 15 fast on the shaft 13. Alined with the sprockets 15 and at the opposite side of the machine therefrom are similar sprockets 16 turning freely in fixed bearings 17. The sprockets 15 and 16 carry 70 chains 18 and these chains are provided at equal intervals in their length with two lugs 19 and 20 projecting at right angles from the outer sides of the runs of the chains and differing from each other only in their 75 length, the lugs 19 being materially longer than the lugs 20. Ample clearance is allowed between the bearings 14 and 17 and their supports for the passage of these lugs. As will be apparent from an inspection of 80 the drawings, the top runs of all the chains above described pass just below the plane of the tops of the rolls of the table. The guide fingers and the two series of lugs should obviously each be alined longitudinally of the 85 table, as is clearly shown in the drawings in order that they may simultaneously engage straight stock lying on the table.

The shafts 5 and 13 may be driven by any motor devices (not shown) adapted to give 90 to each of them turning motion in either direction, and for this purpose I have found the usual hydraulic motor devices satisfactory, although it is to be understood that I do not limit myself to these, as I contemplate using any of the various controlling power devices known in this art.

From the description given it will be seen that by the proper manipulation of the controlling devices the chains 11 and 18 may be 105 driven in either direction so as to position the lugs carried thereby in any desired relation. For instance, if the fingers 12 are held still and the lugs 19 moved toward them with a billet or bar 21 lying between them, 110

the billet or bar will be turned into an upright position and there be held by the conjoint action of the fingers 12 and the lugs 19, as clearly shown in Fig. 2. In this figure successive positions of the lug 19 and bar 21 are shown in dotted lines. If it be desired to turn the bar or billet completely over then the chains 18 are so driven as to bring the short lugs 20 to the top of the table and these co-acting with the fingers 12 will serve to turn the billet or bar over in the manner illustrated in Fig. 4, in which successive positions of a lug 20 and the billet or bar are illustrated in dotted lines. Similar action might be had by maintaining the lugs 19 and 20 stationary while the guide fingers 12 are moved toward them.

The particular feature of the invention being the conjoint use of the lugs and the curved guide fingers, I do not limit myself to the particular means shown for moving the same across the table. Any means which would properly support and guide the lugs and guide fingers transversely across the table might be used and such means will readily suggest themselves to the skilled mechanic. They have been considered and their use is contemplated by me. I prefer, however, the chain mechanism shown as more simple and compact.

The essential feature is the use of an upstanding curved guide finger and a lug, the finger and lug being movable relatively to each other to produce the desired turning action.

Having thus described the invention, what I claim is:—

1. The combination with a receiving table, of a series of upstanding curved guide fingers mounted in longitudinal alinement on the top of said table; and a series of upstanding lugs mounted in longitudinal alinement on said table, movable transversely thereof, and adapted to engage material supported by the table and move it against said guide fingers to turn it about its longitudinal axis, by the rotary guiding action of the curved guides.

2. The combination with a receiving table of a turning mechanism comprising co-acting lugs and curved guide fingers, mounted to move one relatively to the other, and conjointly to engage and turn about its longitudinal axis, through the rotary guiding action of the curved guides, material supported on the table between said fingers and lugs.

3. The combination with a receiving table, of a turning mechanism comprising co-acting curved guide fingers and lugs, each mounted to move relatively to the table, and

adapted when moved toward each other to engage and turn about its longitudinal axis by the rotary guiding action of the curved guides, material supported on the table between them.

4. The combination with a receiving table of two series of transverse conveyer chains, the chains of each series being adapted to be driven simultaneously, and the two series being adapted to be individually controlled; a series of alined upstanding curved guide fingers, one finger mounted on each chain of said first series; and a series of lugs mounted in alinement on the second series of chains; said fingers and lugs being adapted to engage material carried by the receiving table, and to operate conjointly to turn the same.

5. The combination with a receiving table of two series of transverse conveyer chains, the chains of each series being adapted to be driven simultaneously, and the two series being adapted to be controlled independently of each other; a series of upstanding curved guide fingers, one finger mounted on each chain of said first series in alinement longitudinally of said receiving table; and a plurality of series of lugs on the second series of chains, the lugs of different series being of different lengths, and each series of lugs being alined longitudinally of the table, said fingers and lugs being adapted to engage material carried by the receiving table, and the fingers and either series of lugs to operate conjointly to turn the same.

6. In combination with a receiving table having power driven rolls; a plurality of movable members extending across the table beneath the plane of the tops of the rolls; a series of upstanding guide fingers fixedly mounted on some of said members, each of said guide fingers presenting a concave face; and push lugs fixedly mounted on the other members, said lugs and guide fingers being adapted conjointly to engage opposite sides of a billet or the like to turn it about its longitudinal axis.

7. The combination of a receiving table; a curved upstanding guide finger projecting above the top of said table; an upstanding lug projecting above the top of said table; and guiding means for the lug and finger, adapted to guide them in translational motion transversely of the table.

In testimony whereof I have signed my name to this specification in the presence of two subscribing witnesses.

JOHN J. DAVIS.
